(57) **CLAIM**

The ornamental design for a part of food industry machine, as shown and described.

DESCRIPTION

1. Part of food industry machine

1.1: Front view of combination of upper and lower suction hands of the part of food industry machine

1.2: Back view of combination of upper and lower suction hands of the part of food industry machine

1.3: Right view of combination of upper and lower suction hands of the part of food industry machine

1.4: Left view of combination of upper and lower suction hands of the part of food industry machine

1.5: Top view of combination of upper and lower suction hands of the part of food industry machine

1.6: Bottom view of combination of upper and lower suction hands of the part of food industry machine

1.7: Perspective view of combination of upper and lower suction hands of the part of food industry machine

1.8: Perspective view of combination of upper and lower suction hands of the part of food industry machine

1.9: Front view of upper suction hand of the part of food industry machine

1.10: Back view of upper suction hand of the part of food industry machine

1.11: Right view of upper suction hand of the part of food industry machine

1.12: Left view of upper suction hand of the part of food industry machine

1.13: Top view of upper suction hand of the part of food industry machine

1.14: Bottom view of upper suction hand of the part of food industry machine

1.15: Front view of lower suction hand of the part of food industry machine

1.16: Back view of lower suction hand of the part of food industry machine

1.17: Right view of lower suction hand of the part of food industry machine

1.18: Left view of lower suction hand of the part of food industry machine

1.19: Top view of lower suction hand of the part of food industry machine

1.20: Bottom view of lower suction hand of the part of food industry machine

1.21: Reference view of combination of upper and lower suction hands of the part of food industry machine in use state

1.22: Reference view of combination of upper and lower suction hands of the part of food industry machine in use state

(Continued)

1.23: Reference view of combination of upper and lower suction hands of the part of food industry machine in use state

1.24: Reference view of combination of upper and lower suction hands of the part of food industry machine in use state

The reproductions 1.21 to 1.24 are a reference view showing the state in use of the claimed design; the broken lines disclosure in each of the reproductions 1.21 to 1.24 does not form part of the claimed design.
